UNITED STATES PATENT OFFICE.

JAMES MACLEAN, OF BOSTON, MASSACHUSETTS, ASSIGNOR TO UNITED STATES SPECIALTY COMPANY, OF BOSTON, MASSACHUSETTS, A CORPORATION OF MASSACHUSETTS.

WRENCH.

No. 834,312.

Specification of Letters Patent.

Patented Oct. 30, 1906.

Application filed April 25, 1906. Serial No. 313,705.

To all whom it may concern:

Be it known that I, JAMES MACLEAN, a citizen of the United States, residing at Boston, in the county of Suffolk and State of Massachusetts, have invented a new and useful Improvement in Wrenches, of which the following, taken in connection with the accompanying drawings, is a specification.

My invention relates to an improvement to be applied to wrenches whereby the adjustment of the jaws can be easily and quickly made; and it consists of a sliding cam-piece which serves to force and hold the shank of the outer jaw against the shank of the inner jaw, and as a portion of the shank of the inner jaw is provided with a segment of gear-teeth and the shank of the outer jaw with rack-teeth adapted to engage with the said segment-teeth the two jaws may be readily adjusted and held in any desired position in relation to each other.

I attain the desired result by the mechanisms shown in the accompanying drawings, in which—

25 Figure 1 is a side view of one of my wrenches. Fig. 2 is a longitudinal section showing the jaws locked together by the engagement of the teeth of the rack and segment gears. Fig. 3 is a vertical section showing teeth of the rack and segment gear out of engagement with each other, leaving the outer jaw free to move inwardly or outwardly to adapt the wrench to the size of the object to which it is to be applied.

30 In the drawings the body-shank is represented by S. At one end of the shank S a handle H is attached, as shown in Fig. 1. The other end of this shank has the inner jaw J formed on it and also has a segment-gear G, which may be made integral with the shank and jaw or may be formed on a detachable piece which may be attached by a rivet, as shown in Figs. 2 and 3, or in any suitable manner.

45 E is a spring which serves to force the shank A of the outer jaw away from the shank S of the inner jaw and from the segment-gear G.

The outer jaw B has a shank A which has 50 a rack D, the teeth of which engage with the

teeth on the segment-gear G. A casing of sheet metal C C' C² is formed as shown in the drawings and is firmly secured to the shank S by rivets V V, Fig. 1, and has a block of metal R R', also fastened by rivets. The 55 block R R' has a central longitudinal opening K, through which a rod L passes. The forward end of the rod K is bent and formed into a wedge or cam P'. The other end of this rod L has attached to it a thumb-piece 60 N, which also has a cam or wedge N'. A spring T serves to force the cams P' and N' back, as shown in Fig. 2, so that the cam P' will, acting against the shank A of the jaw B, force it down and hold the rack-teeth D in 65 engagement with the teeth of the segment-gear G, and thus hold the jaw in any desired position in which it may be placed by the user.

When the user wishes to move the jaw B 70 forth or back, he places his thumb on the piece N and forces it forward against the spring T. This action forces the cam P' forward and away from the block K. At the same time the cam N is forced under the 75 block K, as shown in Fig. 3. This action allows the forward end of the shank A to free its teeth D from the teeth of the segment G and admits of the free forth-and-back movement of the jaw B. As soon as the user frees 80 the thumb-piece N the rod L, having the cam-wedges P' and N', is thrown back by the action of the spring T into the position shown in Fig. 2, and thus allows the rack-teeth to engage with the segment-teeth and thus securely 85 hold the jaw B in the desired position.

It will be observed from inspection of Figs. 2 and 3 that when a strain is exerted upon the article that is between the jaws the jaw B will swing, as indicated by the arrow V, and that 90 in my wrench this action is possible for the reason that the rack-teeth D of the shank A roll on the teeth of the segment G. Thus I get a gripping action that is very effective.

I claim—

95 A wrench comprising an inner jaw affixed to a shank that forms a part of the handle: a segment-gear attached to said shank: an outside jaw attached to a movable shank, the movable shank having rack-teeth con- 100

structed to engage with the teeth of the said segment-gear: and a spring-operated cam-piece, constructed to be adjusted to lock the outside jaw in any desired position or to 5 leave the jaw free to be moved: substantially as and for the purpose set forth.

In testimony whereof I have signed my

name to this specification, in the presence of two subscribing witnesses, on this 24th day of April, A. D. 1906.

JAMES MACLEAN.
